UNITED STATES PATENT OFFICE.

ERNST G. JENNER, OF CHICAGO, ILLINOIS.

ATTACHMENT FOR RENDERING POWER-PRESSES NON-REPEATING.

1,192,525.

Specification of Letters Patent. Patented July 25, 1916.

Application filed December 22, 1915. Serial No. 68,162.

To all whom it may concern:

Be it known that I, ERNST G. JENNER, a citizen of the United States, residing at Chicago, in the county of Cook and State 5 of Illinois, have invented a certain new and useful Improvement in Attachments for Rendering Power-Presses Non-Repeating, of which the following is a specification.

My invention relates to safety devices for power presses, the object being to prevent 10 the press from repeating unless the operator consciously wills to do so and takes definite steps to have it do so.

The object of the invention is to produce 15 a device of this character which is simple in construction and certain in operation.

It is also my purpose to provide adjustments by which my safety device may be held out of action so that the operator, by 20 keeping the treadle depressed, may cause the press to repeat continuously.

Another object of the invention is to provide means to prevent the operator from accidentally coupling the two parts of the 25 treadle by stepping or otherwise placing the weight upon the treadle shank.

I accomplish my objects by the mechanism illustrated in the accompanying drawings, in which—

30 Figure 1 is a front elevation of a press equipped with my attachment. Part of the view is in section on the line 1—1, Fig. 2. Fig. 2 is a side elevation of a press equipped with my attachment, part of the press being 35 broken away to reveal some of the parts of the attachment. Fig. 3 is a sectional detail on the line 3—3, Fig. 2, showing the pin clutch of the press. Fig. 4 is a perspective view of the chief operating parts of my at- 40 tachment and some of the associated parts of the press. Fig. 5 is a view of the same parts as shown in Fig. 4, but shown in changed position.

Similar numerals refer to similar parts 45 throughout the several views.

My attachment may be applied to presses of various designs. In the design selected to illustrate the invention the slide 1 of the press is operated by an eccentric 2 rigidly 50 fastened on the eccentric or crank shaft 3.

The crank shaft is journaled in the framework 4 of the press and has a fly wheel 5 loosely mounted on it. Power is applied to the fly wheel in any suitable manner. It rotates continuously, while the crank shaft 55 must rotate only when called for. The movement of the fly wheel is transmitted to the crank shaft, when required, by a clutch which may assume various forms. In the form shown, the fly wheel has a disk-like 60 hub 6 and alongside of this is a disk 7 which is keyed or otherwise rigidly fastened to the crank shaft. A clutch pin 8 is slidably mounted in the disk 7 parallel to the axis of the shaft, as shown in section in 65 Fig. 3. When the inner end of the pin enters the socket 9 provided for its reception in the adjacent side of the hub of the fly wheel, the fly wheel and disk will rotate together and cause the crank shaft to rotate. 70 When the pin is withdrawn, the fly wheel will continue to rotate but the shaft will stand still. A spring 10 constantly urges the pin toward the fly wheel hub. A clutch fork 11 is slidably mounted in a bracket 75 12 attached to the side of the machine frame and guides the fork toward and from the clutch pin. Said pin has a notch 8^a formed in the side, and when the fork has fully entered the notch it holds the pin in non- 80 acting position. The bracket 12, contains a spring 13 which constantly urges the fork toward the pin. The front end of the fork is beveled or cam shaped to enable it to enter the notch when the pin is in acting 85 position and gradually withdraw the pin from the fly wheel hub as the pin travels around the axis of the shaft. In other words, if the fork spring 13 is permitted to act, it forces the fork up into the path 90 of the pin and this automatically throws the clutch "out." As soon as the clutch is out the clutch disk 7 ceases to rotate and hence will remain quiet until the fork is depressed and thus made to release the clutch pin. As 95 soon as the pin is thus released, it automatically engages the fly wheel hub and causes the crank shaft to rotate. The fork is controlled by a chain 14 or equivalent device. In the form shown, the pin 8 con- 100

stitutes a connecting element and the fork 11 a lock-out element for locking the connecting element in non-active position.

In my device the clutch chain 14 is not connected directly to the treadle 16, (or at least to the portion carrying the pedal 17) but is indirectly connected thereto through the agency of a novel combination of elements which will now be described.

- 10 In my construction the clutch chain is connected to an element 20 which for identification may be called the clutch-controlling lever. It is fulcrumed upon a stationary rod 21 mounted in the base of the machine frame. In the particular instance illustrated, the chain is connected to said lever about midway between its ends. By preference, lever 20 is in the form of an inverted channel fitting over the treadle. The rear 15 end of the treadle is pivotally supported by a pin 22, which is mounted in said lever, by preference, approximately midway between its ends. The exact position of pin 22 relatively to said lever, is, however, non-essential. The parts are so constructed and arranged that when held up only by pin 22, it will drop down onto the floor, or at least it will drop down until its adjustable screw stop 23 rests upon the floor. But with my 20 device the treadle will normally be held up in close contact with the lever 20 by a crank or eccentric 25 which is fulcrumed upon a pin 26 carried by a post 27 rising from and rigidly secured to said lever. A pair of 25 links 28 are pivotally connected with crank 25 by a pin 19 located at a point sufficiently remote from the fulcrum pin 26 and at their lower end said links carry a cross bar 29 upon which the treadle rests. The proportions are such that when the crank 25 is rotated to acting position, as shown in Fig. 4, the treadle will lie in close contact with the lever 20 and be capable of operating it to control the clutch, but when said crank is 30 rotated to non-acting position, as shown in Fig. 5, the treadle will lie upon the floor and be incapable of affecting the clutch. In this position it may be said to be "out of gear." Crank 25 has a leg 25^a adapted to descend 35 on to the top of the clutch-controlling lever 20 as shown in Figs. 2 and 4. In rotating to this position the pin 19 travels slightly beyond a line passing vertically through the pin 26. Hence the crank may be said 40 to have passed beyond center, or to be overbalanced, and as a result the weight of the links 28 and of the treadle carried thereby, holds the crank safely in acting position.

In my device the treadle may be thrown 45 out of gear manually and automatically. The manually operated mechanism consists of a pull rod 30 connected to the outer end of the arm 25^b of the treadle crank 25. Said rod is guided by a stationary bracket 31

which holds the front end of the rod within 65 convenient reach of the operator.

The automatic means for throwing the treadle out of gear will now be described: A lever 35 is fulcrumed on the rod 21 and at its forward end is connected by a link 36 70 to the treadle crank 25. Between its ends, lever 35 is connected to a link which in turn is connected to a cam operated lever 37. Said link consists of two bars 38 and 39, the bar 38 having a lengthwise slot 40 for 75 accommodating a screw 41 projecting from bar 39 and carrying a wing nut 42 by which the parts may be fastened together. This provides for lengthwise adjustment of the parts. In the best design, bar 38 is provided with a pin 44 capable of entering any one of a series of holes 43 in bar 39. This makes for security when the parts have been brought to the proper adjustment. Lever 37 is fulcrumed upon a stationary stud 45 80 projecting in the present design from the side of bracket 12. An antifriction roller 46 is mounted at the end of lever 37 remote from the point of attachment of bar 39. This, under normal running conditions, lies 85 in the path of the cam 48 formed on the periphery of the clutch disk 7.

In operation, let it be assumed that the operator desires to operate the press under normal running conditions under which the 90 slide will descend only when the treadle is depressed. He first pulls the rod 30 and sets the crank 25 in acting position, shown in Fig. 4, which will thus lock the treadle to the clutch-controlling lever 20 and cause said 95 parts to act as a single piece. If, now, the operator depresses the treadle he causes the chain 14 to descend and withdraw the fork 11 from the clutch pin 8, thus permitting the 100 spring 10 to throw said pin into the socket 9 in the hub 6 of the fly wheel. This locks the clutch parts together and causes the shaft 3 to rotate and the slide to descend. Now, if the operator promptly releases the 105 treadle and permits it to rise completely, 110 (under the influence of the spring 13) the clutch fork will rise early enough to engage the clutch pin before the latter has made a complete revolution about the axis of the 115 shaft and will withdraw the pin from the hub of the fly wheel. This will disconnect the main shaft from the power and permit the shaft to come to rest. But operators do not always release the treadle promptly 120 enough and they frequently fail to permit the treadle to rise completely. My device prevents the press from repeating under such conditions, for the cam 48 is so located on the clutch disk 7 that unless the treadle is completely raised, said cam will engage 125 the roller 46 and, acting through the parts 37, 38, 39, 35 and 36, throw the crank 25 to non-acting position, thus uncoupling the

treadle (or throwing it out of gear) as shown in Fig. 5. This permits the clutch-controlling lever 20 to rise independently of the treadle and permits the clutch fork to rise in time to engage the clutch pin 8, and withdraw it from the fly wheel hub before the slide commences to descend the second time. Said cam 48 is timed to operate ahead of the time that the clutch fork would normally engage the clutch pin to throw it out and hence there is no possibility of the press repeating accidentally because before the press can repeat the cam 48 will have acted and thrown the treadle out of gear. After the treadle has once been thrown out of gear it cannot be again coupled to the lever 20 until the crank 25 is deliberately returned to acting position through the medium of the pull rod 30 or otherwise.

The stop 23 is provided as an extra precaution to prevent the treadle from being accidentally thrown back into gear by reason of a weight falling on it or the operator putting his foot on it accidentally at a point near the end of lever 20. This will be best understood by referring to Fig. 5, in which the treadle is shown with its outer end resting upon the floor. Suppose the stop 23 were absent, and the operator in resetting his dies or attending to some other duties about the press should step upon the treadle near the outer end of the lever 20, the outer end of treadle, resting upon the floor, would act as a fulcrum point, and the weight of the operator would have the effect of lowering the pin 22. On account of the arrangement of the parts, this would cause the pin 26 to descend faster than the pin 19 and rotate the crank 25 from non-acting to acting position. This would recouple the treadle to the lever 20 and cause the press to repeat without the operator intending it to do so. I have thus provided a stop or supplemental support in the treadle at a point remote from the outer end thereof to prevent the treadle from being accidentally thrown into gear by being subjected to a weight at a point remote from the outer end of the treadle. Of course, there are occasions when it is desirable to have the press repeat continuously so long as the operator holds the treadle depressed. I have arranged for this by making the connecting link 33, 39 adjustable as to length in the manner previously described. By adjusting this link so that its effective length is longer than under the conditions above described, the anti-friction roller 46 will be permanently held out of reach of the cam 48 and will, therefore, be unaffected by it.

It will be understood that I use the word "treadle" because the controlling element in presses is usually in the form of a foot-operated element. I wish it understood, how-

ever, that I consider that a hand-operated element would be essentially the same thing and would come within the scope of my invention.

Having thus described my invention what I claim as new and desire to secure by Letters Patent, is—

1. In a safety attachment for power presses, a power press having a clutch and a clutch-controlling lever, in combination with a treadle, and means manually actuated to connect and manually actuated to disconnect the treadle to and from the lever whereby said lever and treadle will operate in unison, or said treadle will be movable independently of said lever.

2. A power press having a clutch and a clutch-controlling lever, in combination with a treadle pivotally supported at its inner end adjacent to said lever, and a crank connected to both the treadle and lever, said crank when in one position locking the lever and treadle together and when in another position permitting the lever to move independently of the treadle.

3. A power press having a clutch and a clutch-controlling lever, in combination with a treadle pivotally supported at its inner end adjacent to said lever, a crank connected to both the treadle and lever, said crank when in one position locking the lever and treadle together and when in another position permitting the lever to move independently of the treadle, and means for controlling the position of said crank.

4. A power press having a slide, a main shaft for operating said slide, a clutch for throwing said shaft into and out of connection with the power, and a lever for controlling said clutch; in combination with a treadle, a crank connected to both the treadle and lever for coupling and uncoupling them, and automatic means operated by said shaft for throwing said crank to the position in which the treadle and lever will be uncoupled.

5. A power press having a slide, a main shaft for operating said slide, a clutch for throwing said shaft into and out of connection with the power, and a lever for controlling said clutch; in combination with a treadle, a crank connected to both the treadle and lever for coupling and uncoupling them, a cam on said shaft, and connections between said cam and said crank for throwing said crank to non-acting or uncoupled position when acted upon by said cam.

6. A power press having a slide, a main shaft for operating said slide, a clutch for throwing said shaft into and out of connection with the power, and a lever for controlling said clutch; in combination with a treadle, a crank connected to both the

1
treadle and lever for coupling and uncoupling them, a second lever having a pivotal axis coincident with the axis of the clutch-controlling lever, said second lever being connected to said crank for throwing it to non-acting position, a rotating cam operated by said shaft, and connection between said cam and said second lever for operating said second lever to throw said crank to non-acting position.

10 7. A power press having a slide, a main shaft for operating said slide, a clutch for throwing said shaft into and out of connection with the power, and a lever for controlling said clutch; in combination with a treadle, a crank connected to both the treadle and lever for coupling and uncoupling them, a rotating cam operated by said shaft and a link-and-lever connection between said cam and said crank for throwing said crank to non-acting position, said connection including an extensible, adjustable link which, when extended, holds the connection out of reach of said lever.

15 8. A power press, having a slide, a main shaft for operating said slide, a clutch for throwing said clutch into and out of connection with the power, and a lever for controlling said clutch; in combination with a treadle pivotally supported at its inner end upon said lever, a crank mounted upon said lever, connections between said crank and said treadle whereby, when the crank is in acting position, the treadle and lever will move in unison and when said crank is thrown to non-acting position said lever is free to move independently of said treadle, a cam rotating in unison with the main shaft, and means actuated by said cam for throwing said crank to non-acting position.

20 9. A power press, having a slide, a main shaft for operating said slide, a clutch for throwing said clutch into and out of connection with the power, and a lever for controlling said clutch; in combination with a treadle pivotally supported at its inner end upon said lever, a crank mounted upon said lever, connections between said crank and said treadle whereby, when the crank is in acting position, the treadle and lever will move in unison and when said crank is thrown to non-acting position said lever is free to move independently of said treadle, a cam rotating in unison with the main shaft, a pair of levers, in addition to the first, one of the levers of the pair being connected to the crank for operating it and the other lever of the pair being normally subject to the action of said cam, and a link connecting said pair of levers, said link being adjustable as to length, whereby the lever which is normally acted upon by the cam, may be permanently held out of reach of said cam.

25 10. A power press having a clutch, and a clutch-controlling lever; in combination with a treadle pivoted at its inner end to said lever, and a stop on said treadle for preventing the depression of the inner end of said treadle when the outer end of the treadle is held against descent.

30 11. A power press having a clutch and a clutch-controlling lever, in combination with a treadle pivoted at its inner end to said lever, means for coupling and uncoupling said treadle and lever, said lever being able to rise independently of the treadle when the parts are uncoupled, and a stop remote from the outer end of the treadle for preventing the descent of the inner end of the treadle when the outer end of the treadle is held against descent.

35 12. A power press having a clutch and a clutch-controlling lever, in combination with a treadle pivoted at its inner end to said lever, means for coupling and uncoupling said treadle and lever, said lever being able to rise independently of the treadle when the parts are uncoupled, and a stop remote from the outer end of the treadle for preventing the descent of the inner end of the treadle when the outer end of the treadle is held against descent, said stop being mounted upon said treadle and vertically adjustable with reference thereto.

40 13. A power press having a continuously rotating power device, a slide, a clutch for causing said shaft to operate said slide, said clutch having a connecting element tending normally to assume acting or connecting position when said power device reaches a predetermined point in its rotation, said connecting element rotating in unison with said power device when the clutch is "in", a lock-out element movably mounted upon a stationary part of the machine for holding said connecting element in non-acting position, said lock-out element normally engaging said connecting element prior to the point in its rotation where said connecting element would normally move to acting position, a manually operated element normally preventing said lock-out element from locking out said connecting element, and a rotary cam acting upon said manually operated element in advance of the point where said lock-out element tends to engage said connecting element, to thereby render said manually operated means ineffective to prevent said lock-out element from locking out the connecting element.

45 14. A power press having a continuously rotating power device, a slide, a clutch for causing said shaft to operate said slide, said clutch having a connecting element tending normally to assume acting or connecting position when said power device reaches a predetermined point in its rotation, said

connecting element rotating in unison with said power device when the clutch is "in", a lock-out element movably mounted upon a stationary part of the machine for holding 5 said connecting element in non-acting position, said lock-out element normally engaging said connecting element prior to the point in its rotation where said connecting element would normally move to acting 10 position, a lever for moving said lock-out element to a position where it will not act

upon said connecting element, a treadle for operating said lever, said treadle being connectible to and disconnectible from said lever, and a rotary cam for disconnecting 15 said lever from said treadle, said cam being timed to act in advance of the point where said lock-out acts upon said connecting element.

In witness whereof, I have hereunto subscribed my name.

ERNST G. JENNER.
